Primary Examiner—Louis S. Zarfas*Assistant Examiner*—Eric Watterson*Attorney, Agent, or Firm*—Goldstein & Canino[57] **CLAIM**

The ornamental design for a toilet seat handle, as shown and described.

DESCRIPTION

FIG. 1 is a perspective view of the toilet seat handle in full lines with a toilet and toilet seat, the seat being in the raised position, shown in broken lines representing environmental association matter being for illustrative purposes only and forming no part of the claimed invention;

FIG. 2 is a perspective view of the toilet seat handle in full lines with a toilet and toilet seat, the seat being in the lowered position, shown in broken lines representing environmental association matter being for illustrative purposes only and forming no part of the claimed invention;

FIG. 3 is an enlarged elevational view of the toilet seat handle;

FIG. 4 is a rear elevational view thereof;

FIG. 5 is a bottom plan view thereof;

FIG. 6 is an enlarged top plan view of the toilet seat handle; and,

FIG. 7 is a right side elevational view thereof, the left side view being a mirror image of the right side view.
